Primary Examiner — Robert Delehanty*(74) Attorney, Agent, or Firm* — Banner & Witcoff, Ltd.(57) **CLAIM**

The ornamental design for a tub filler, as shown and described.

DESCRIPTION

FIG. 1 is a right perspective view of a tub filler showing my new design;

FIG. 2 is a left perspective view thereof;

FIG. 3 is a left side view thereof;

FIG. 4 is a right side view thereof;

FIG. 5 is a front view thereof;

FIG. 6 is a rear view thereof;

FIG. 7 is a top view thereof; and,

FIG. 8 is a bottom view thereof.

The broken line showing of the spout opening at the wall and dispensing ends and the rear lower notch is for environmental purposes only and forms no part of the claimed design.

1 Claim, 8 Drawing Sheets(56)
